7 Claims. (Cl. 60—52)

I

This invention relates to hydraulic systems of the kind in which a continuously running high speed pump is used to supply pressure liquid to actuate a hydraulic press under the control of an automatically operating valve.

In practice it is found that a fluctuating pressure occurs in the pressure supply main to the press and it is the object of the present invention to overcome this trouble in a simple and reliable manner.

The improved system according to the present invention comprises in combination a continuously running high-speed pump, an automatically operating unloading valve for unloading the pump chambers when the pressure in the delivery main reaches a predetermined maximum, a master control valve actuated by the pressure in the pump delivery main to supply liquid at a lower pressure for actuating the unloading valve and interposed between the pump delivery and the press or other hydraulic machine to be actuated, and a reducing valve interposed in the main pressure line between the outlet of the master control valve and the inlet of the press or other hydraulic cylinder.

To enable the invention to be understood and carried into effect an arrangement of apparatus forming a practical embodiment of the improved system will now be described by aid of the accompanying figures, in which:

Fig. 1 is a sectional view of the fluid supply pump and the unloading valve for controlling the pump output.

Fig. 2 is a sectional view of the master control valve interposed between the supply pump and the reducing valve.

Fig. 3 is a sectional view of the reducing valve included in the hydraulic circuit between the master control valve and the hydraulic press.

The system illustrated in the drawing comprises a high speed multi-ram reciprocating pump A adapted for continuous running, an automatically operating valve B for unloading the pump chambers of the pump A when the pressure in the delivery main reaches a predetermined maximum, a master control valve C adapted to be actuated by the pressure in the pump delivery main to supply liquid at a lower pressure for actuation of the unloading valve B, and a reducing valve D arranged so as to control the flow of pressure liquid to a press or other hydraulic apparatus.

As will be seen from the drawings, the pump delivery main 1 is connected to the pressure liquid inlet 19 of the master control valve C by means of a pipe 2. The pressure liquid inlet 3 of the unloading valve is connected with the reduced

pressure outlet 4 of the master control valve by means of pipe 5. The high pressure liquid outlet 6 of the master control valve is connected to the inlet 7 of the reducing valve by pipe 8 whilst a further pipe 9 connects the outlet 10 of this reducing valve to the hydraulic machine, for example the pressure supply main of one or more hydraulic presses (not shown). The unloading valve B comprises an automatically operating plunger 11 which is moved longitudinally and relative to a discharge outlet 12 in the wall of each pump bore 13, said outlets 12 being additional to the usual valve controlled pump discharge outlets 14, and said longitudinal movement being effected against a spring 15 constituting a predetermined load. For thus moving the plunger 11 the pressure liquid is admitted to a space 16 and it there acts against a piston 17 and a ram 18, the piston being of substantially larger area than the ram on which it is mounted for independent relative movement. With this arrangement the first part of the plunger's stroke is effected by the pressure liquid acting against the combined areas of the piston 17 and the ram 18 and this movement is utilised, in the illustrated example, to unload two of the pump chambers. The unloading of the last or third pump chamber in the series is effected by the ram alone and this requires a substantial rise to occur in the pressure liquid before it can take place owing to the much smaller area presented to the pressure liquid by the ram than was presented by the combined areas of the piston and the ram which was available for imparting the first part of the unloading stroke. This enables the last pump bore, or pump where separate pumps are under control, to be cut in and out rapidly to supply make-up liquid to a hydraulic system, for example to counteract normal leakage, with the other pump chamber or pumps remaining unloaded.

The unloading valve B described above constitutes in part the subject matter of our United States Patent No. 2,478,213, filed February 17, 1944, and issued August 9, 1949. The master control valve C, which will be presently described, constitutes in part the subject matter of our co-pending United States application Serial No. 522,844, filed February 17, 1944, now Patent No. 2,561,431, issued July 24, 1951.

The master control valve C as illustrated comprises an inlet 19, with which the outlet 6 has free communication through the intermediary of an annulus 20, an orifice 40, and a non-return valve 21.

Within the valve body, and surrounded by

annular chambers 20 and 25 is a bore 26 for the reception, in a close sliding fit, of a valve plunger 27. The annular chambers 20 and 25 are in communication with the interior of the bore 26 by means of two sets of radial passages, one set 28 connecting the bore with the lower annular chamber 20 and the other set 29 connecting the bore with the upper annular chamber 25. A further set of radial passages 30 is provided to connect the chamber 25 with the bore at a point above the set of passages 29 to connect the chamber 25 with the exhaust outlet 23 when the valve plunger is in its lower position. In passing from the chamber 25 to the exhaust outlet 23 the fluid goes through passages 30, the upper end of bore 26, space 43, the duct 41, the circular passage 42 around the cylinder 44 of the pressure relief valve 22, and the conduit 45.

Annular grooves 46 and 47 are cut in the exterior surface of the valve plunger 27 so as to encircle the same. These grooves are spaced longitudinally a distance equivalent to the distance between the centers of the sets of radial passages 28 and 29 with which they are adapted to register when the valve plunger is in the raised or open position shown in Fig. 2. The grooves 46 and 47 communicate with a longitudinal passage 49 within the interior of the valve plunger 27 by means of radial holes 50 and 51. By this means a passage for liquid is provided between the annular chambers 20 and 25 when the valve plunger is in the raised position and said chambers are isolated from each other when the valve plunger is in the lowered position. Because of the symmetrical location of the fluid chambers the plunger 27 is always in hydraulic balance laterally.

At opposite ends of the valve plunger 27 are spaces 43 and 52 which are always in free communication with the exhaust outlet 23. The communication passage for space 43 is through the duct 41, the circular passage 42, and the conduit 45. The conduit 54 forms a communication passage between space 52 and exhaust outlet 23. It is apparent that the interconnection of the spaces 43 and 52 with the exhaust outlet 23 will produce equal pressures in the spaces, thereby tending to place the plunger 27 in hydraulic balance longitudinally. The space 43 is closed at the upper end by a suitable packing 39.

In Fig. 2 the valve plunger 27 is shown in the raised position and passing liquid at a predetermined pressure from the pump to the auxiliary apparatus. The movement of the plunger to the raised position is effected against the spring 55 by pressure liquid acting upon the lower or full pressure side of piston 56. The piston stem 57 enters the space 52 and abuts against the lower end 59 of the valve plunger 27.

The pressure liquid which acts against the under side of the piston 56 is supplied through the one-way valve 21 from the annular chamber 20. This pressure liquid is routed to both sides of the piston 56 in the cylinder 60 in which the piston reciprocates. Conduits 61 and 62 carry fluid to the upper end of the piston 56 and conduits 61 and 64 channel fluid to the lower end of the piston 56. A non-return valve 66 is positioned in the conduit 64 to pass liquid freely to the under side of the piston 56. When pressure in the conduit 61 falls, the influence of the spring 67 will cause the valve 66 to close automatically and prevent liquid from escaping.

from the lower end of the cylinder 60. The liquid thus trapped below the piston 56 is permitted to escape at a relatively slow rate by leakage between the piston 56 and the side walls 60 of the cylinder to the upper end of the cylinder 60. Sufficient clearance is provided between the piston 56 and the cylinder wall 60 to permit liquid to escape past the piston 56 so that the piston and the plunger 27 will descend under the influence of the spring 55 at the desired rate.

By means of the arrangement just described, the pressure liquid is permitted to act against the effective area of the piston 56 equal to the area of the stem 57. When this pressure is sufficient to overcome the resistance of the spring 55, the valve plunger 27 is forced upwardly to the position illustrated in Fig. 2. By thus permitting the pressure liquid from the valve inlet 19 to have free access to the under side of the piston 56, the valve plunger 27 is rendered fully sensitive to and is immediately actuated by a sudden increase in the pressure of the said liquid. By restricting the escape of the liquid from the under side of piston 56 as previously described, the return movement of the valve plunger 27 and the spring 55 is damped to minimize hunting caused by increases and decreases of the fluid at the inlet 19 and in the conduits 61.

When the plunger 27 is in the raised position, illustrated in Fig. 2, pressure liquid is free to pass to the outlet 4 and at the same time the relief valve 22 is subject to its pressure. The path of the liquid from the inlet 19 to the outlet 4 and the relief valve 22 is through the annulus 20, radial passage 28, annular groove 41, radial hole 50 in the plunger 27, longitudinal passage 49, radial hole 51, annular groove 46, radial passages 29, and annular chamber 25. The chamber 25 communicates with outlet 4 and relief valve 22 through channels 91 and 92 respectively. By suitably setting this relief valve it is able to blow-off at a predetermined pressure below the pressure of the liquid at the inlet 19. This master control valve thus supplies to the unloading valve for its operation, pressure liquid at any required pressure below the delivery pressure in the pump delivery main.

The example of reducing valve illustrated in the accompanying drawing comprises a spring pressed plunger 31, shown in the partly raised position, having a reduced portion 31a in its length which, when the plunger is in the normal lowered position bridges passages 69 and 70 connecting the inlet 7 and outlet 10. A space 32 at the bottom of the plunger is in open communication through bores 71, 72 and 73 with the pressure inlet 7. A counterbore 78 is provided through which bores 71 and 72 are interconnected. When this liquid which presses upwardly on the lower end of plunger 31 attains a pressure sufficient to overcome the downward pressure of the spring pressed plunger said plunger is forced upwards to isolate the inlet 7 from the outlet 10 and to open the inlet to exhaust. The exhaust fluid flows through passage 69, the annular space 74 between the reduced portion 31a of the plunger 31 and the cylindrical opening 75 in which the plunger reciprocates, the radial outlets 76 and the circular clearance space 77 between the lower spring seat 79 and the inside diameter 80 of the upper casing 81, into the enclosed space 82 of the upper casing 81. From this space the exhaust fluid is free to pass around the upper spring

seat 84 and out the exhaust nipple 85 and exhaust line 86. When the pressure has dropped sufficiently the plunger moves downwards under influence of spring 87 to reopen the communication between the aforesaid inlet 7 and outlet 10. Some of the fluid in the space 32 below the plunger 31 is displaced by the downward movement of the plunger 31. This fluid flows back through the hoses 73, 72, and 71 to the inlet 7 where it travels through the valve along with additional fluid entering through inlet 7. By this means the pressure of the liquid passing out through the outlet 10 is maintained substantially constant. It is evident that the pressure to which the liquid at the outlet 10 is reduced is determined by the pressure required to raise the plunger 31 against the spring 87. This latter pressure and hence the outlet pressure may be adjusted by means of the adjusting screw 88 provided in the upper end of the casing 81. This screw determines the position of the upper spring seat 84 to regulate the residual pressure of the spring 87 on the plunger 31. Adjustment of the screw determines the maximum pressure that may be delivered to the hydraulic machine through pipe 9. A suitable protective cap 90 is provided for covering the upper end of the screw 88.

We claim:

1. A hydraulic system comprising, in combination, a fluid motor, a continuously running pump for supplying fluid under pressure, means forming a supply passage interconnecting said pump and said motor to conduct fluid under pressure from said pump to said motor for actuating said motor, a plurality of pump chambers in said pump in communication with said supply passage, an unloading valve associated with said pump chambers for controlling the output of said pump by unloading at least one of said chambers in response to a predetermined fluid pressure, a pressure responsive master control valve interposed in said supply passage, said master control valve constituting means operable upon attainment of a predetermined pressure in said supply passage for diverting fluid at less than the maximum pump discharge pressure from said supply passage to said unloading valve for actuating said unloading valve to control the output of said pump, and a pressure reducing valve interposed in said supply passage between said master control valve and said fluid motor.

2. A hydraulic system of the kind specified, comprising in combination with a hydraulic motor, a high speed multi-ram pump having plural chambers and adapted to run continuously for supplying liquid for actuating said hydraulic motor, a main pressure line interconnecting said pump chambers and said hydraulic motor, an automatically operating unloading valve for unloading the respective pump chambers when the pressure in said main pressure line therefor reaches a predetermined maximum, said unloading valve being operable to unload at least one of the pump chambers at different time relation with respect to the others and under different pressure values, a master control valve actuated by the pressure in the pump delivery main, said control valve constituting means for diverting liquid to said unloading valve at a lower pressure than the maximum pump delivery pressure for actuating the unloading valve, said master control valve being interposed in said main pressure line between

5 the pump delivery and the hydraulic motor to be actuated, and a pressure reducing valve interposed in said main pressure line between the master control valve and the hydraulic motor.

3. A hydraulic system of the kind specified, comprising in combination with a hydraulic motor, a pump having a plurality of chambers and adapted to run continuously for supplying liquid for actuating said hydraulic motor, a delivery main interconnecting said hydraulic motor and said pump, an automatically operating unloading valve for unloading said respective pump chambers when the pressure in said delivery main therefor reaches a predetermined maximum, said unloading valve being operable to unload at least one of said pump chambers at different time relation with respect to the others and under different pressure values, a control valve actuated by the pressure in the 10 pump delivery main to divert liquid from said delivery main to said unloading valve for actuating said unloading valve, said control valve being interposed in the delivery main between the pump delivery and the hydraulic motor to be actuated, and a pressure reducing valve interposed in the delivery main between the control valve and the hydraulic motor.

4. A fluid system comprising in combination, a fluid motor, a fluid pump for supplying actuating fluid to said motor, a plurality of chambers in said pump, means defining a fluid passageway between said chambers and said motor, an unloading valve having exhaust ports corresponding in number to the number of said 15 chambers, said exhaust ports being paired with said chambers with each port communicating with a single chamber, a control member associated with said exhaust ports for controlling said pump by unloading any number of said 20 chambers, a pressure responsive control valve interposed in said fluid passageway, said control valve constituting means for diverting fluid from said passageway to said control member for controlling said pump, and a pressure reducing valve 25 interposed in said fluid passageway between said control valve and said fluid motor.

5. A hydraulic system comprising, in combination, a continuously running pump for supplying fluid under pressure to a fluid motor, 30 means defining a supply passage for conducting fluid under pressure from said pump for delivery to said motor, said pump having a plurality of pump chambers in delivery communication with said passage, an unloading valve 35 associated with said pump chambers and operable normally to maintain said pump chambers loaded and operable in response to a predetermined rising pressure gradient successively to unload said chambers whereby to control the output of said pump, a master control valve 40 interposed in said supply passage and having a fluid diverting outlet and being responsive to the pressure in said passage to divert fluid from said passage to said outlet upon the attainment of pressure above a predetermined pressure in said supply passage, and a control passage 45 interconnecting said outlet and said unloading valve for transmitting the pressure of diverted fluid to act on said unloading valve, said control valve also being operable to relieve the pressure in said control passage upon a drop in pressure in said supply passage below said predetermined pressure.

6. A hydraulic system for supplying fluid 50 under pressure to a hydraulic motor, comprising,

in combination, a hydraulic pump having a plurality of pump chambers and a delivery outlet, a supply passage for conducting fluid from said outlet and adapted for connection to said motor, an unloading valve associated with said pump chamber and having pressure responsive control means operable to unload at least one of said chambers upon being subjected to a first predetermined elevated pressure and to unload said one and still another of said chambers upon being subjected to a higher second predetermined pressure and operable to effect loading of said chambers in reverse order upon being subjected to pressures dropping progressively below said predetermined pressures, means defining a control passage connected to said unloading valve to transmit pressure to said control means, and a master control valve interposed in said supply passage, said control valve permitting the flow of fluid past it through said supply passage and having means defining a diverting passage connected to said control passage and control means normally tending to close said diverting passage and responsive to the pressure in said supply passage to open said diverting passage upon the attainment of a third predetermined pressure in said supply passage and successively to close

10

15

20

25

said diverting passage and vent said control passage to exhaust upon a progressive drop in pressure below said third predetermined pressure.

7. A hydraulic system according to claim 6 including a pressure reducing valve interposed in said supply passage at the downstream side of said control valve.
